UNITED STATES PATENT OFFICE.

MARVIN H. MOONEY, OF GAULT, MISSOURI.

HAY-STACKER.

SPECIFICATION forming part of Letters Patent No. 716,738, dated December 23, 1902.

Application filed May 7, 1902. Serial No. 106,329. (No model.)

To all whom it may concern:

Be it known that I, MARVIN H. MOONEY, a citizen of the United States, residing at Gault, in the county of Grundy and State of Missouri, have invented certain new and useful Improvements in Hay-Stackers, of which the following is a specification.

This invention relates to certain new and useful improvements in hay-stackers of that type in which the fork is carried by swinging arms mounted to move in the arc of a circle from a substantially horizontal to a substantially vertical position; and the purpose of the present improvement is to embody in a device of this class two stackers connected for simultaneous operation, whereby when one is elevated and delivering its load the other is lowered to receive a load or jag, the two stackers being so organized as to practically counterbalance and operated by a horse-power from which extend cables or the like, the slack on one cable directly operating in connection with one stacker loosening the remaining portion of the cable connecting with the other stacker.

A further object of the invention is to facilitate the formation of a stack and elevate more hay or straw within a given time by the same amount of power than is usually required to operate one stacker and also to embody in each of the stackers, which are co-operatively related, means for topping the stack.

With these and other objects and advantages in view the invention consists in the construction and arrangement of the several parts, which will be more fully hereinafter described and claimed.

In the drawings, Figure 1 is a perspective view of a stacker embodying the features of the invention and shown arranged in operative position. Fig. 2 is a rear elevation of one of the stackers shown elevated and a part of the frame supporting the same. Fig. 3 is a detail plan view of an attachment used in connection with each fork for locking the tines in position for topping. Fig. 4 is a transverse vertical section through the supporting-frame for the stacker, showing one of the stacking devices in edge elevation and positions of adjustment in dotted lines. Fig. 5 is an enlarged edge elevation of a portion of one of the forks. Fig. 6 is a transverse

vertical section through a portion of the supporting-arms of one of the stackers, showing means for lengthening or shortening said arms. Fig. 7 is a top plan view of the horse-power device particularly arranged for use with the double stacker and showing a portion of the frame of the latter. Fig. 8 is a longitudinal vertical section through the center of the horse-power, with a portion of one of the base-runners of the stacker-frame shown in side elevation.

Similar numerals of reference are employed to indicate corresponding parts in the several views.

The numerals 1 and 2 designate, respectively, elongated runners, which form the base structure for the entire device and with the parts attached thereto are adapted to be dragged over the ground-surface to the place or position where it is desired to erect or form a stack. Secured to the upper edges of the runners 1 and 2 are cross-strips 3, which hold the said runners in positive spaced relation and in upright position, the said strips being terminally extended beyond the outer side of the runner 1. The strips 3 for a greater portion of their length are formed with longitudinal slots 4, which extend through the ends thereof connected to the upper edge of the runner 2, and pivotally secured in the said ends of the strips resting on the runner 2 are compensating bars 5, one being located in each strip and steadied in their rising and lowering movements by brace-rods 6, attached thereto and movably connected to the upper edge of the runner 2 on opposite sides of the point of attachment of the strip 3. As both stacking devices are similar in construction, one only will be particularly described. On opposite sides of the strip 3 the lower ends of members 7 of the fork-arms are pivotally connected to the runner 1, and co-operating therewith are upper members 8, the respective members 7 and 8 being terminally provided with angular sleeves 9, slidably engaging said members and held in adjustable position in relation to the latter by pins or bolts 10, whereby the arms are made telescopically adjustable to accommodate different heights of the stack during the formation of the latter. It will be understood that the engaged extremities of the members 7 and 8 will be supplied with a suit-

able number of apertures to accommodate an adjustment of the said arms, and attached to the ends of the members 7, adjacent to the sleeves thereon, are the upper ends of stop-cables 11, which have intermediate devices 12 of a suitable nature for supporting counterpoise or balancing weights 13, as clearly shown in dotted lines by Fig. 4, when it is found necessary to use such weights. The said intermediate devices 12 are in the form of slides which may be moved longitudinally over the stop-cables 11 to apply the weights at any point along the length of said cables which may be found necessary in the operation of the stacker. It is obvious that these stop-cables 11 prevent the fork-arms from swinging over too far, but permit the fork to assume such angle that it will readily become unloaded or allow the charge or jag of hay or straw carried thereby to slip over onto the top of the stack. The upper members 8 are connected to the head of an elevating fork or rake 14, comprising a plurality of tines 15, arranged in parallel planes with the said members 8 and having a corresponding series of angular tines 16 pivotally connected thereto. For ordinary stacking purposes the tines 16 are permitted to occupy the angle shown by Fig. 1; but when it is desired to top the stack the said tines 16 are elevated, as indicated by dotted lines in Fig. 4, and held in such position by a keeper 17, comprising a bar 18, pivotally mounted at its ends to one of the fork or rake bars and adapted to be thrown upwardly under the tines 16. Between the lower extremities of the members 8 and the head of the fork or rake 14 braces 19 are located and connected at opposite terminals, respectively, to the fork or rake head and the lower terminals of the members 8. The braces 19 relieve the fork-arms of strain, particularly when the said arms are elevated during the elevating operation thereof, and connected to the free end of the compensating bar 5 are the two ends of pull-rods or analogous devices 20, which diverge and are attached at their opposite ends to the fork or rake head, the said pull-rods or analogous devices removing the pulling strain direct from the arms of the fork and transferring it to the said fork. These pull-rods or analogous devices 20 are intermediately separable to accommodate lengthening and shortening of the arms, and when the members 8 of the arms are projected their full extent the upper portions of the pull-rods are used. When the arms are telescoped, the upper portions of the pull devices are detached from the lower portions of said devices and folded into the heads of the forks, as shown by Fig. 2, and held against movement by the said lower portions of the pull devices, which then have their upper ends connected to the heads of the forks.

With the improved double stacking organization a particular form of horse-power is used, and comprises opposite runners 22, connected by a cross-strip 23, to the center

of which a sweep 24 is pivotally attached on the upper squared end 25 of a center post 26, rotatably mounted and vertically disposed in the said strip 23, the center post having its lower extremity depending below the strip and also squared, as at 27, to receive a cable-attaching arm 28, provided with a loop swivel or eye 29 in its outer end for this purpose. Through the medium of the center post 26, constructed as set forth, the sweep 24 and arm 28 are caused to move simultaneously and equally in proportion to their length, and at a suitable elevation in the runners 22 are a pair of guide-sheaves 30, disposed in a horizontal plane and in longitudinal alignment. The sweep 24 is also supplied with suitable draft-attaching appliances, such as a singletree, and is long enough to permit a horse attached thereto to travel around the runners 22. The terminals of an operating-cable 31 or the like are secured to the eye 29 on the arm 28, and the opposite portions of said cable are passed over the exterior portions of the sheaves 30, the one part of the cable extending away from the inner side of one runner 22 and the other part from the outer side of the opposite runner. That part of the cable which extends away from the inner side of one runner passes over a sheave 32, horizontally disposed in the front extremity of the runner 2 of the stacker organization, directly under the secured end of the forward strip 3, and thence transversely across and through an opening 33 in the forward extremity of the runner 1, over a vertically-disposed sheave or pulley 34 in the end of the strip 3, which projects outwardly over said runner 1, and thence to the free end of the adjacent compensating-bar 5. The other part of the cable 31 passes through a sheave or pulley 35, secured at an intermediate point on the outer side of the runner 1, thence through a pulley or sheave 36 on the end of the other cross-strip 3, and is terminally connected to the adjacent compensating bar 5. It will be seen that the cable 31 through the connection thereof to the arm 28 virtually becomes a continuous cable terminally attached to the two compensating bars. The purpose of connecting the cable-terminals to the bars 5 is to relieve the pulling strain directly from the arms of the forks or rakes, so as to prevent fracturing or breaking said arms, and the liability to injury of the arms is further prevented by the use of the pull-rods or analogous devices 20, heretofore explained and also attached to the compensating bars.

The horse-power devices, as well as the compound stacking structure disclosed, may be simultaneously moved from one place to another by dragging the same over the ground-surface through the medium of connecting-rods 37, detachably secured to the front ends of the runners 1 and 2 and the rear ends of the runners 22, as clearly shown by Fig. 7; but after the apparatus as an entirety has been disposed in the position desired the

said connecting-rods may be detached and the horse-power moved any distance desired from the stacking organization itself.

When the improved device as an entirety is arranged for use, the parts will be disposed as shown by Fig. 1, one set of arms and their forks being lowered and the other elevated and the horse-power placed at a distance from the front extremities of the runners 1 and 2. 5 To permit the arms of each fork or rake to lower very close to the ground-surface, the upper edge of the runner 2 at the front and rear extremities is formed with slots 38, into which the arms of the forks or rakes are 10 adapted to be depressed, as clearly shown by Fig. 1. The improved device having been arranged in convenient position to the quantity of straw or hay to be stacked, the arm 24 is set in rotative motion by means of a draft-animal, the one fork being first loaded with the hay or straw by an operator, it being understood that the fork or rake which is loaded 15 will be the one that is in lowered position. When the sweep 24 is moved from the position 20 shown by Fig. 1 in the direction of the arrow, the right-hand portion of the cable 31 will be drawn forwardly by the arm 28, and thereby gradually elevate the forward fork or rake by pulling on the compensating bar 5, which when the said fork or rake is lowered will stand in an approximately vertical 25 position. The pulling force of the said right-hand portion of the cable will be exerted through the compensating bar and the pull-rods or analogous devices 20 and concentrated 30 on the head of the fork or rake, and as the said forward fork or rake is elevated the left-hand portion of the cable is gradually slackened or moved rearwardly and allows 35 the rear fork or rake to lower, and when said rear fork or rake is at its lowest position it is loaded and immediately starts to elevate just at the time that the forward fork or rake is unloaded or has deposited its load 40 on the stack. This elevating operation of the rear fork will occur when the sweep 24 arrives at a point approximately opposite that shown by Fig. 1, and simultaneously the forward fork will begin to lower, and thus 45 the alternate elevating operation of the two fork structures is carried on regularly without reversing the draft-animal and during the continuous movement of said animal in one direction. This is due to the fact that when 50 the arm 28 terminally arrives in its closest relation to the two sheaves or pulleys 30 of one runner 22 all the slack necessary in the one portion of the cable to permit the fork or rake structure controlled thereby to fully

lower will have been exhausted and the pulling strain on the other portion of the cable necessary to elevate the remaining fork structure will have been completed, and immediately the fork structure that has been lowered will start to rise or elevate and the one that was elevated will lower. By this means a stack may be quickly formed, and in view of the fact that the two fork structures counterbalance each other or are exact counterparts in weight the draft-animal is only required to lift approximately the same load weight, and, in fact, the load weight will be slightly decreased in view of the assistance in pulling the cable, due to the lowering of the empty fork structure. 60

The improved device is comparatively simple in its construction, and in view of the economical operation and expedition resulting in the formation of a stack owing to the dual fork organization a very useful farming 70 implement will be produced.

Having thus fully described the invention, what is claimed as new is—

1. A hay-stacker having dual fork structures adapted to be alternately raised and lowered by pulling power applied from a single source. 80

2. A hay-stacker having dual fork structures and power appliances adapted to alternately elevate and depress the same. 90

3. A hay-stacker having dual fork structures of equal weight adapted to alternately elevate and depress, and a cable device connected to the said structures and actuated from a single power-producing medium. 95

4. A hay-stacker having fork structures adapted to alternately elevate and depress, the elevation of one structure assisting in the depression of the other and vice versa.

5. A hay-stacker comprising a pair of independent fork organizations, and operating devices correlative connecting said organizations whereby when one is elevated the other will be depressed, and vice versa. 100

6. A hay-stacker comprising a pair of independent fork organizations movably mounted to alternately elevate and depress, a horse-power having an arm, and an operating pull device made continuous through attachment to said arm and terminally connected to said 105 fork organizations.

In testimony whereof I affix my signature in presence of two witnesses.

MARVIN H. MOONEY.
